UNITED STATES PATENT OFFICE.

ROSS M. BICKLEY, OF PITTSBURGH, PENNSYLVANIA, ASSIGNOR TO HEYL & PATTERSON, INC., OF PITTSBURGH, PENNSYLVANIA, A CORPORATION OF PENNSYLVANIA.

APPARATUS FOR HANDLING COAL.

1,251,626.

Specification of Letters Patent.

Patented Jan. 1, 1918.

Application filed March 13, 1915. Serial No. 14,156.

To all whom it may concern:

Be it known that I, Ross M. BICKLEY, a citizen of the United States, and resident of Pittsburgh, in the county of Allegheny and State of Pennsylvania, have invented a new and useful Improvement in Apparatus for Handling Coal; and I do hereby declare the following to be a full, clear, and exact description thereof.

10 My invention relates to apparatus for handling coal.

My invention comprises the novel features hereinafter set forth and claimed.

Referring to the drawings, Figure 1 is a plan view; Fig. 2 is a side view partly in section; Fig. 3 is an enlarged section on the line 3—3, Fig. 1; Fig. 4 is an enlarged section on the line 4—4, Fig. 1; Fig. 5 is an enlarged section on the line 5—5, Fig. 1; Fig. 20 6 is a detail showing the manner in which the refuse is discharged from one of the tables. Fig. 7 is an enlarged section on the line 7—7, Fig. 1; and Fig. 8 is an enlarged longitudinal section.

25 In the drawings, the numeral 2 designates the chute leading from a suitable screening device, said chute comprising the upper deck 3, the middle deck 4, and the lower deck 5. The upper deck 3 delivers the lump-coal to the 30 rotary picking-table 6; the deck 4 delivers the egg-coal to the rotary picking-table 7; and the deck 5 delivers the slack to the loading or boom-conveyer 8.

The rotary tables have the annular 35 troughs 9 to receive the coal to be picked. The tables are provided with the rails 10 engaged by the wheels 11 journaled in uprights 12 supported on a suitable structure. The tables may be driven by any suitable 40 power as illustrated and described in connection with the above application.

The table 6 has the inner and outer refuse-chutes 13 into which the slate or other impurities are discharged by the pickers, and 45 said chutes radiate from a central chute 14 to which the refuse is directed to be discharged into a suitable receptacle.

The table 6 rotates in the direction of the arrow, and a plow or baffle 15 directs the 50 picked coal into the loading-conveyer 8.

The picking-table 7 is preferably located at a slightly higher elevation than the table 6, and the coal is fed to said table by the deck 4 with the downward extension 16. 55 The table 7 rotates in the direction of the

arrow, or opposite to the direction of rotation of the table 6, and said table is provided with the swinging-plow or baffle 17, which may be arranged to direct the picked coal by the chute 18 over onto the table 6 60 when it is desired to mix the two grades of coal, or by swinging said baffle over into the position indicated in dotted lines, the coal is directed off by the chute 19 to the loading conveyer 20. By having the table 7 slightly 65 elevated above the table 6, the discharge of the coal therefrom is by gravity.

The table 7 is provided with the inner and outer chutes 21 for the reception of the refuse picked from the coal, and said chutes 70 deliver the coal to the pan 22, which is carried by the picking-table 7 and rotates therewith. This pan 22 is supported by the annular plate-girder 23, which extends down from the table 7 and said girder has openings 24 at intervals through which the refuse passing down through the inner chutes 21 is discharged into the pan 22. A guard-plate 25 is provided to collect any refuse 75 which may fall from the inner chutes 21, 80 and said plates being arranged on a slant, will direct the refuse through the openings 24 in the plate-girder 23.

The refuse carried around in the pan 22 is delivered into the chute 26 by means of the 85 baffle 27. The refuse is carried by gravity down the chute 26 into the central refuse-chute 14 of the table 6.

By my invention, the lump-coal is directed to the table 6; the egg-coal to the table 7; 90 and the slack to the loading conveyer 8 or 20 as may be desired; and to provide for the directing of the slack to either of said conveyers, the deck 5 is provided with the upwardly swinging gate 28 as indicated in 95 dotted lines, Fig. 2.

The coal after having been picked in the table 6, is directed into the loading-conveyer 8, while the refuse is discharged into the central-hopper 14. If it is desired to mix 100 the egg-coal picked in the table 7 with the lump-coal of table 6, the baffle 17 is swung to the position indicated by full lines in Fig. 1, whereupon the egg-coal is directed by the chute 18 onto the table 6 adjacent to 105 the chute 15, and is carried along with the lump-coal into the loading-conveyer 8. If, on the other hand, it is desired to separate the lump and egg-coal, the baffle 17 is moved to the position shown in dotted lines, Fig. 1, 110

whereupon the egg-coal is delivered by the chute 19 into the loading-conveyer 20. As clearly stated above, the slack may be either directed into the loading-conveyer 8 or 20, 5 as desired.

What I claim is:

1. In coal handling apparatus of the character described, the combination of a rotary picking-table, means for delivering the coal thereto, chutes for the refuse, a common chute with which said chutes communicate, a second picking table at a higher level than said first table, means for delivering coal to said second table, a chute leading from said second table to said first table, chutes for the refuse adjacent to said second table, a pan below said second table and carried thereby communicating with said last named chutes, and means for directing the refuse from said pan to the common refuse chute of said first table.
  2. In coal handling apparatus of the character described, the combination of a rotary picking-table, means for delivering coal thereto, chutes for refuse adjacent said table, a common refuse chute communicating with said chutes below said table, a second rotary picking-table at a higher level than said first table, chutes for the refuse adjacent said second table, a pan below said second table carried thereby and with which said last named chutes communicate, a baffle in the path of said pan, and a chute leading from said pan to said common refuse chute of said first table.
  3. In coal handling apparatus of the character described, the combination of a rotary picking-table, means for delivering coal thereto, chutes for refuse adjacent said table, a common refuse chute communicating with said chutes, a second rotary picking-table at a higher level than said first table, means for delivering coal to said second table, refuse chutes adjacent said second table, a chute leading from said second table to said first table, and a movable baffle controlling the movement of the coal to said last-named chute.
  4. In coal handling apparatus of the character described, the combination of a rotary picking-table, means for delivering coal thereto, a loading conveyer adjacent said table, means for directing the coal from said table to said loading-conveyer, a second rotary picking-table, means for delivering coal thereto, a loading conveyer adjacent said second table, means for directing the coal from said second table to said last-named loading conveyer, and a slack-chute having its forward end in communication with said

first-named loading-conveyer, and having an opening registering with said second loading-conveyer, and a door controlling said opening.

5. In coal handling apparatus of the character described, the combination of a rotary picking-table, means for supplying coal thereto, a loading-conveyer adjacent said table, means for directing the coal from said table to said loading-conveyer, a second rotary picking table at a higher level than said first table, a chute leading from said second table to said first table, a second loading-conveyer chute leading from said second table to said second loading-conveyer, and a movable baffle for directing the coal into said chute leading to said first table or to the chute leading to said second loading-conveyer. 65
70
75

6. In coal handling apparatus, the combination of a rotary picking-table, means for supplying coal thereto, chutes for refuse adjacent said table, an annular plate extending below said table having openings therein, and a pan carried by said table, said refuse chutes extending down in close proximity to said plate. 80 85

7. In coal handling apparatus of the character described the combination of an annular rotary picking-table, means for supplying coal thereto, chutes for refuse on the inside of said picking-table, an annular plate extending below said picking-table, having openings therein, and a pan carried by said table, said refuse chutes extending down in close proximity to said annular plate. 90 95

8. In apparatus for handling coal of the character described, the combination of a rotary picking-table, impurity chutes, an annular plate carried by said table below the same, and having openings therein, a pan carried by said table, said impurity chutes extending down in close proximity to said plate, and a guard-plate carried by said table on said plate. 100

9. In apparatus for handling coal of the character described, the combination of a rotary picking-table, means for delivering coal thereto, a second rotary picking-table at a higher level than said first table and non-concentric therewith, means for delivering coal to said second table, and a chute leading from said second table to said first table. 110

In testimony whereof, I the said Ross M. BICKLEY, have hereunto set my hand.

ROSS M. BICKLEY
